APPARATUS FOR VARYING THE CHARACTERISTICS OF AEROSOLS

Leonard Bonameau, Brussels, Belgium, assignor to Societe Anonyme Teco, Liege, Belgium

Application March 18, 1948, Serial No. 15,628
In France March 19, 1947

7 Claims. (CL. 183—80)

1

In the employment of aerosols (micelles or infinitely small liquid or solid particles in suspension in a gas or in air) it is often found desirable to be able to regulate their characteristics, and in particular to be able to regulate between certain limits the dimensions of the particles emitted by the aerosol generator, above all when the aerosols are utilised for disinfection or for therapeutical treatment. In fact it is frequently necessary to eliminate from the aerosols particles which exceed a given size, and the object of the present invention is to effect this elimination by simple and effective means.

According to the invention this result is obtained by reason of the fact that the aerosols, in their passage from the outlet of the generator to the place where they are to be used, are submitted to a controllable action of centrifugal force. It will be understood that in submitting a current of aerosols to the action of centrifugal force, one first of all causes sedimentation of the larger particles, since this force is proportional to the mass of the particles and the square of the speed. For a given effect of centrifugal force, there will be obtained the sedimentation of the particles the dimensions of which exceed a given value. For regulating this value the invention provides a corresponding regulation of the said effect, either by varying the intensity of the centrifugal force, that is, the speed imparted to the micelles, or by varying the duration of this effect, which then remains constant, on the aerosols. It is obvious that one can vary simultaneously, the intensity of the centrifugal force and the duration of its action.

The invention also relates to an apparatus for carrying into effect this process, this apparatus comprising, between the generator and the place where the aerosols are to be used, an adjustable curvated passage imparting a gyratory movement to the aerosols in order to subject the latter to a controllable effect of centrifugal force. This adjustable passage is conveniently formed by a conduit the volume of which can be adjusted, either by variation of its section, so as to vary the passage section and thus the speed of flow of the current of aerosols and the intensity of the centrifugal force, or by variation of its length, so as to vary the duration of the effect of a constant centrifugal force. Use may also be made of a conduit having an adjustable curvature.

Other peculiarities and advantages of the invention will be seen from the following description of several forms of construction according to the invention with reference to the attached

diagrammatic drawings, and in which Figures 1 to 9 show part sectional elevations of nine different forms of construction of the apparatus according to the invention, and in which

5 Fig. 1 shows an embodiment having an adjustable resilient helical member defining the curvated passage;

Fig. 2 is an embodiment having a helical member slightly different from that of Fig. 1;

Figs. 3 and 4 illustrate similar embodiments in which the curvated passage is in the form of a groove;

Fig. 5 shows an embodiment where the wall of the container defines a curvated passage the length of which can be varied by a plug, and

Figs. 6, 7, 8 and 9 show similar embodiments of the invention in which the curvated passage is defined by tubular members.

In the example illustrated in Fig. 1, the apparatus comprises the cap 1 containing the product to be atomised, a nozzle 2 projecting the pulverised product against a permeable screen 3 formed by a perforated sheet or plate of metal or of insulating material and a cylindrical envelope 4 which fits the cap and contains the said screen. A sleeve 5 is mounted to slide on a cylinder 6 arranged co-axially within the envelope 4. This sleeve is guided in a neck on the cover 1 of the envelope and may be secured in any desired position by means of a locking screw 8. A resilient helix 9, the interior edge of which contacts the cylinder 6 and the exterior edge of which contacts the envelope 4 is fixed by one of its ends directly or indirectly to the cylinder 4 at 10 and at its other extremity to the cylinder 5 at 11.

The aerosols having traversed the screen 3 pass along the helical path bounded by the helix 9 and leave the apparatus at the outlet 12. The gyratory movement thus imparted to the aerosols removes from the latter the largest particles which return to the cap 1. By regulating the position of the sleeve 5 one may compress or extend the helix 9, which latter remains in contact with the cylinders 4 and 6, so as to modify the transverse section of the conduit which it bounds and to increase or reduce the speed of the aerosols and thus the intensity of the action of centrifugal force.

In the totally raised position of the sleeve 5, the micelles leaving at 12 will be of the upper limit of size. They will, on the other hand, be smallest when the helix 9 is compressed to the maximum.

In the construction illustrated, the screen 3 retains the majority of the moist particles, that is to say, those which have not been sufficiently

finely divided to form a true aerosol. The elimination of these moist particles may equally be effected by any other suitable means.

It is also possible to project the atomised liquid obliquely against the wall of the envelope 4, so as to impart the said atomised liquid an impulse about the axis of the apparatus, and then to introduce it into the helical conduit.

In the modified form of construction shown in Fig. 2 use is made of a resilient free helix 13 compressed between the screen 3 and the plug 14 which latter has a sliding fit within the envelope 4 and may be secured in any desired position by means of the locking screw 15. The outlet 16 extends through this plug. The ends of the helix are formed so as to avoid fouling the surfaces engaging therewith. Under the effect of movement of the plug 14 the helix twists or untwists whilst maintaining its internal and external edges respectively in connection with the cylinders 4 and 6.

The helix of Figs. 1 and 2 may be replaced by a resilient rolled tube in the form of a helix with connecting turns. In compressing this tube along the axis of the helix a more or less pronounced ovalisation or flattening of its transverse, originally circular, section is produced, thus varying the area of this section.

The apparatus shown in Fig. 3, as well as that shown in Fig. 4, is based on the variation of the duration of the centrifugal action by causing the aerosols to pass through a conduit of constant helical section but of varying length.

As shown in Figure 3, a cylinder 17 in which a peripheral helical groove 18 is formed, is mounted to slide freely within the envelope 4. To the latter is fixed a stud 19 which fits exactly in the groove 18 and guides the cylinder 17 in such a fashion as to move the latter longitudinally in the envelope 4, in the direction corresponding to that of the rotation which is imparted to it. The aerosols pass through the helical conduit as far as the stud 19, and leave by the outlet 20 fixed to the envelope 4, in front of the said stud, which latter blocks the part of the helical conduit which is above it. It is sufficient to regulate the height to which cylinder 17 is introduced within the envelope 4 to obtain aerosols the micelles of which have the necessary restricted dimensions between the given limits.

The same result may be obtained by other suitable means. As shown in Fig. 4, the cylinder 17 may be mounted to rotate about its axis without longitudinal movement with respect to the envelope 4, the stud 19 thus being eliminated. The envelope 4 is perforated with a series of openings 21, 22, 23 . . . disposed in such a manner that when the cylinder 17 is turned one of these openings always covers a point on the helical groove 18, as a result of which the aerosols escape into a lateral casing 24 and finally leave at 20. The aerosols are thus collected at a height varying with the angular position of the cylinder 17, after having been subjected for a variable time to the action of centrifugal force so that the dimensions of the micelles vary accordingly.

In the form of construction according to Fig. 5, the jet of aerosols produced by the nozzle 2 is directed obliquely upwards, tangentially to the cylindrical envelope 4, and issues with a helical trajectory between the envelope 4 and the concentric guiding cylinder 25, leaving through a conduit 26 provided in a plug 27 which is integral with the cylinder 25 and has a sliding fit within the envelope 4, a locking screw 28 en-

abling it to be fixed in any desired position. The axial displacement of the cap varies the length of the passage of the aerosols and thus the duration of the effect of centrifugal force.

It is also possible to employ a movable nozzle 2, for example one mounted to rotate about an axis perpendicular to the axis of the cylinder 4, so as to be able to vary the pitch and thus the length of the helical trajectory travelled by the flow of aerosols between the cylinders 4 and 25, which may then be fixed the one with respect to the other. The cylinders 4 and 25 may be replaced by truncated cones or other surfaces of revolution.

Although the cylinder 25 is not theoretically indispensable, its employment is desirable in practice in order to prevent dispersion of the jet of aerosols.

In the examples shown in Figs. 6 to 9, a lid 125 is placed on the envelope 4 and is provided with an outlet 126 through which the aerosols escape into the adjustable passage imparting a gyroscopic movement to the aerosols.

In the construction according to Fig. 6, this passage is constituted by a flexible and preferably elastic tube 127, which forms a curved passage and has one end attached to the outlet 126, whereas its other end is connected to the point where the aerosols are used, for example a mouthpiece 128 if the aerosols are to be used for inhalations. The tube 127 may, for example, be made of elastic metal, rubber or the like, advantageously reinforced by a helical spring with practically touching turns.

It will be sufficient to move the end 128 towards or away from the outlet 126 in order to contract or expand the curved passage of the tube 127 so as to cause the action of the centrifugal force to vary and produce the sedimentation of a more or less important part of the larger particles. The volume and the section of the tube remain practically unchanged, but the centrifugal acceleration changes with the inclination of the curved passage, for instance the pitch of the helix if the curved passage is helical, whereas the diameter may also vary during the displacements.

In the example shown in Fig. 6, the curved passage is of helical form, although it may also have another form, for instance that of a spiral.

The displacements of the tube 127 may be obtained by means of any convenient mechanism, for example by acting upon a screw-coupling box 29 having inner screw threads of opposite pitch extending respectively over half of its length, and cooperating with two screw-threaded rods 30, 31 having also threads of opposite pitch and one of which is secured, for example welded, to the lid 125, whereas the other is bent at an angle and supports the upper end of the tube 127 by means of a collar 32.

Figs. 7 and 8 show particularly simple constructions, the aerosols evacuated through the lid 125 passing through a curved conduit having the form of a U, for instance with a pointed (33 in Fig. 7) or a rounded (34 in Fig. 8) base. A median partition 35 is slidably mounted in a guide 37 which is integral with the curved conduit and embraces the said partition in a fluid-tight manner. The position of the partition may be continually or gradually adjusted, for example by means of a pin 38 engaging a hole provided in the guide and in any one of a series of holes 39 provided in the movable partition. In this manner it is possible to vary the

section and the average length of the curvated conduit the concave wall whereof is formed by the surface of the partition 35 which also permits of adjusting the rate of sedimentation of the greater particles.

As shown in Fig. 9, the movable element may form the outer wall of the curvated conduit 40, instead of constituting the inner wall thereof. The movable element 41 is mounted in a guide 42 integral with the conduit 40, in a manner similar to that of the partition 35 or 36.

The term "curvated" used in the specification and claims for defining the passage of the aerosols includes as well the curved form as that which is determined by a succession of angular deviations, as shown for instance in Figs. 7 and 9.

It is obvious that the invention is not limited to the examples illustrated, but may be equally carried out in various other forms of construction. Thus the helical path may be replaced by a spiral path the length of which is regulated and which is twisted to a greater or lesser degree in order to vary the curvature of the spirals. The various members may be provided in any suitable materials for example in metal, glass, plastic or moulded material or the like, and if necessary in an electrically insulated material.

What I claim is:

1. A device for regulating the characteristics of aerosols for therapeutical use comprising, in combination, a closed chamber, a nozzle disposed in said chamber to discharge aerosols into said chamber, a curvated variable passage having smooth walls adapted to impart centrifugal movement to a column of aerosols, separating means adapted to remove moistening particles from the aerosols disposed between said nozzle and said curvated variable passage, a discharge opening for the aerosols at the end of said passage, and externally adjustable means adapted to adjust the conformation of said passage during the operation of the device, thereby controlling the effective centrifugal force acting on the aerosols in said passage and producing sedimentation of oversize particles on the walls of said passage while maintaining the smooth walls thereof in curved form.

2. A device for regulating the characteristics of aerosols for therapeutical use comprising, in combination, a closed chamber, a nozzle disposed in said chamber to discharge aerosols into said chamber, a curvated variable passage having smooth walls adapted to impart centrifugal movement to a column of aerosols, separating means comprising a perforated member constituting a screen adapted to remove moistening particles from the aerosols disposed between said nozzle and said curvated variable passage, a discharge opening for the aerosols at the end of said passage, and externally adjustable means adapted to adjust the conformation of said passage during the operation of the device, thereby controlling the effective centrifugal force acting on the aerosols in said passage and producing sedimentation of oversize particles on the walls of said passage while maintaining the smooth walls thereof in curved form.

3. A device for regulating the characteristics of aerosols for therapeutical use comprising, in combination, a closed chamber, a nozzle disposed in said chamber to discharge aerosols into said chamber, a curvated variable passage having smooth walls adapted to impart centrifugal movement to a column of aerosols, separating means comprising a perforated member consti-

tuting a screen adapted to remove moistening particles from the aerosols disposed between said nozzle and said curvated variable passage, a discharge opening for the aerosols at the end of said passage, and externally adjustable means adapted to adjust the conformation of said passage during the operation of the device, thereby controlling the effective centrifugal force acting on the aerosols in said passage and producing sedimentation of oversize particles on the walls of said passage while maintaining the smooth walls thereof in curved form, said variable passage being substantially U-shaped and being disposed at the end of said chamber and having an opening adapted to slidably receive said externally adjustable means.

4. A device for regulating the characteristics of aerosols for therapeutical use comprising, in combination, a closed chamber, a nozzle disposed in said chamber to discharge aerosols into said chamber, a curvated variable passage having smooth walls adapted to impart centrifugal movement to a column of aerosols, separating means comprising a perforated member constituting a screen adapted to remove moistening particles from the aerosols disposed between said nozzle and said curvated variable passage, a discharge opening for the aerosols at the end of said passage, and externally adjustable means adapted to adjust the conformation of said passage during the operation of the device, thereby controlling the effective centrifugal force acting on the aerosols in said passage and producing sedimentation of oversize particles on the walls of said passage while maintaining the smooth walls thereof in curved form, said variable passage being disposed above said nozzle, and said chamber forming a receptacle below said nozzle adapted to receive the oversize particles collected on said perforated member and on the walls of said curvated passage.

5. A device for regulating the characteristics of aerosols for therapeutical use comprising, in combination, a closed chamber of substantially cylindrical conformation, a nozzle disposed in said chamber to discharge aerosols into said chamber, a curvated variable passage having smooth walls adapted to impart centrifugal movement to a column of aerosols, separating means comprising a perforated member constituting a screen adapted to remove moistening particles from the aerosols disposed between said nozzle and said curvated variable passage, a discharge opening for the aerosols at the end of said passage, and externally adjustable means adapted to adjust the conformation of said passage during the operation of the device, thereby controlling the effective centrifugal force acting on the aerosols in said passage and producing sedimentation of oversize particles on the walls of said passage while maintaining the smooth walls thereof in curved form, said perforated member extending transversely of said chamber above said nozzle.

6. A device for regulating the characteristics of aerosols for therapeutical use comprising, in combination, a closed chamber of substantially cylindrical conformation, a nozzle disposed in said chamber to discharge aerosols into said chamber, a curvated variable passage having smooth walls adapted to impart centrifugal movement to a column of aerosols, separating means comprising a perforated member constituting a screen adapted to remove moistening particles from the aerosols disposed between

said nozzle and said curvated variable passage, a discharge opening for the aerosols at the end of said passage, and externally adjustable means adapted to adjust the conformation of said passage during the operation of the device, thereby controlling the effective centrifugal force acting on the aerosols in said passage and producing sedimentation of oversize particles on the walls of said passage while maintaining the smooth walls thereof in curved form, said perforated member extending transversely of said chamber above said nozzle, and said curvated variable passage being defined by a resilient helical member extending radially from a central longitudinal section to freely contact the walls of said chamber with a sliding fit and extending axially from a position above said nozzle to said externally adjustable means.

7. A device for regulating the characteristics of aerosols for therapeutical use comprising, in combination, a closed chamber of substantially cylindrical conformation, a nozzle disposed in said chamber to discharge aerosols into said chamber, a curvated variable passage having smooth walls adapted to impart centrifugal movement to a column of aerosols, separating means comprising a perforated member constituting a screen adapted to remove moistening particles from the aerosols disposed between said nozzle and said curvated variable passage, a discharge opening for the aerosols at the end of said passage, and externally adjustable means adapted to adjust the conformation of said passage during the operation of the device, there-

10 by controlling the effective centrifugal force acting on the aerosols in said passage and producing sedimentation of oversize particles on the walls of said passage while maintaining the smooth walls thereof in curved form, said perforated member extending transversely of said chamber above said nozzle, said curvated variable passage being defined by a movable cylindrical element provided with a helical groove and having a sliding fit in said chamber and said externally adjustable means including a stud projecting from the wall of said chamber into said groove.
